DRIVING AND STOPPING MECHANISM

Joseph Gouldbourn, Thomas Aubrey Kestell, and Frank Bycroft Keall, Leicester, England, assignors to United Shoe Machinery Corporation, Paterson, N. J., a corporation of New Jersey

Original application September 7, 1933, Serial No. 688,480. Divided and this application February 18, 1935, Serial No. 7,016. In Great Britain October 11, 1932

20 Claims. (Cl. 192—144)

This invention is concerned with improvements in or relating to starting and stopping mechanisms particularly applicable to sewing machines for operating on thick stubborn materials such as leather.

An illustrative machine of this kind is disclosed in United States Patent No. 1,169,909 granted to Fred Ashworth, February 1, 1916, and also in the present inventors' co-pending application, Serial No. 688,480, filed September 7, 1933 for Sewing machine from which application the present application has been divided.

Usual machines of this kind employ mechanism for actuating the sewing instrumentalities which, while satisfactory for enabling the machine to sew efficiently, up to a speed of say five hundred stitches per minute or thereabouts, is not suited for enabling the machine to run at a relatively high speed, for example, to sew a thousand stitches per minute.

The objects of the invention are to provide novel and improved starting and stopping means particularly well adapted for stopping without shock and invariably at the same point in its cycle such a high speed machine as is contemplated.

With these and other objects in view, the present invention contemplates the provision in a high speed machine having a main shaft, a main clutch, high and low speed clutches, of means for opening the main clutch while the low speed driving clutch is closed. In the machine described, the means for opening the main clutch is actuated by the main shaft automatically when the speed of the shaft is reduced sufficiently to be driven by the low speed clutch and a brake is provided to stop the machine with the parts in a predetermined position after the main clutch is opened.

In order that the nature of the present invention may be more clearly understood, an illustrative embodiment will now be described and the above objects of the invention and its several features will become apparent to those skilled in the art from said description.

In the drawings:

Figure 1 is a view from the left hand side showing the general form of the illustrative machine; Figure 2 is a sectional view illustrating the high and low speed clutches on a countershaft of the machine; Figure 3 is a sectional view showing the driving and stopping mechanism on the main shaft of the machine; Figure 4 is a detail view looking from the left of the machine showing certain elements associated with the stopping mech-

anism of the machine; Figure 5 is a plan view illustrating part of the stopping mechanism of the machine; Figure 6 is an end view from the left hand side of the machine showing certain parts of the stopping mechanism seen in Figure 5; and Figure 7 is a plan view showing part of the clutch tripping mechanism shown in Figure 5.

The said illustrative embodiment of the invention is a machine designed for sewing the outsoles of welted shoes to their welts and comprises a column 1 and a head casting 5. A main shaft 15 is arranged parallel to the front of the machine (i. e. from left to right) and has mounted on it a main driving clutch arranged to be driven by belts from a countershaft secured to the column 1. The arrangement of the clutch (the construction of which will be described in detail hereinafter) is such that the shaft 15 is caused to run normally at a high speed in a clockwise direction looked at from the left of the machine when the starting treadle is fully depressed but can be caused to run at a low speed in the same direction by causing or allowing the treadle to occupy a position higher than its fully depressed position. Shaft 15 has secured to it cranks and other awl mechanisms which actuate needle and other awl mechanisms of the machine.

The countershaft for transmitting power to the main shaft 15 and high and low speed driving clutch embodying the present invention will now be described. The countershaft 18 (Fig. 1) is supported in bearings 20, 22 secured to the machine near the lower end of the column and has fast and loose pulleys 24, 26 over which a belt passes from suitable line shafting. The countershaft has freely mounted on it a relatively small grooved pulley 28 coupled by a round belt 30 to a relatively large pulley 32 (Fig. 2) mounted on the main shaft 15 and a relatively large grooved pulley 34 which is arranged on shaft 18 behind the smaller pulley 28 is coupled by a belt 36 to a relatively small pulley 38 on the main shaft. Secured to the countershaft so as to rotate therewith, but being movable axially along it between the large and small pulleys 34 and 28 is a driving member 40 in the form of a disc which has fixed to its rear face a leather ring 42 arranged to engage and grip the large pulley 34 when the driving member 40 is moved rearwardly. The driving member 40 also has fixed on its front face a leather ring 44 which engages the small pulley 28 when moved forwardly. The driving member 40 has fixed to it a pin 46 which passes through a slot extending along and passing through the axis of the countershaft 18. A spring pressed

plunger 48 mounted in the countershaft engages the pin 46 and normally presses the driving member forwardly into engagement with the small pulley 28 so that the small pulley is normally coupled to the countershaft. A circular plate 50 is secured to the countershaft in front of the small pulley and has a leather ring 52 secured to its rear face. The relatively small pulley 28 is free to move to a slight extent along the shaft and when the driving member 40 is moved along the shaft into engagement with it, the relatively small pulley is urged against the plate 50 and clamped between it and the driving member when the machine is being started. The driving member 40 is arranged to be moved to cause the machine to run at high speed against the action of the spring pressed plunger 48 away from the small pulley towards and into engagement with the large pulley by a treadle 54, normally raised by a spring 56 connected by an upwardly extending link 58 having universal connections at its ends to an arm 60 extending laterally from the end of a screw 62 which is threaded into and through a fixed sleeve 64 supported by a bracket 66 on the machine column. The rear end of this screw bears against the forward end of a stud 68 mounted in a bore in the forward end of the countershaft and bears at its rear end against the pin 46 in the driving member 40. The arrangement is such that when the treadle is raised the driving member engages the small driving pulley and by depressing the treadle the screw 62 is moved rearwardly, moving the driving member rearwardly out of engagement with the small pulley and into engagement with the large pulley. The arrangement of the pulleys of the high and low speed driving clutch on the main shaft 15 of the machine is as follows. A bell-shaped member 70 encloses the left end of shaft 15 and pulley 38 is formed on the outside portion of the bell-shaped member. As shown in Fig. 3, the pulley 38 has two grooves in either of which the belt may be run to give a choice of high speeds.

To the rim of the bell shaped member 70 is secured a disc-like member 72 which has a relatively long sleeve 74 encircling shaft 15 and is rotatably mounted upon a bush 76. Thus the disc-like member 72 forms a carrying member for the bell-shaped member 70. The relatively large pulley 32 is formed as an annulus mounted on the periphery of the disc-like member 72 and is prevented from moving axially by contact with, respectively, a face on the bell-shaped member 70 and a radial flange on member 72. A radial bolt 78 (Fig. 3) passes through the relatively large pulley 32 and clamps to the inner face thereof a small block 82 within a recess 84 cut in the member 72. The recess 84 is approximately twice the length of the block 82 and provides a lost motion device between the high speed and low speed pulleys 38 and 32. The block 82 has a pin 86 projecting from its left face and engages the forked end of a short swinging lever 88, the inner end of lever 88 having a wedge-shaped portion 89 engages a recess in a stem 90 parallel to the main shaft 15 and housed within the sleeve 74 of the disc-like member. The said short swinging lever is pivoted about midway of its length on a pin 92 extending from member 72. The left hand end of the stem 90 projects beyond the end of shaft 15 and is turned inwardly across the latter. Shaft 15 has a bore 94 containing a sliding rod 96 (normally urged towards the right by a spring 98) and its left end is threaded. Nuts 100 are provided on the threaded end of rod 96

to couple the rod to the stem 90 through which it passes. The right hand end of rod 96 has fixed in it a pin 102 which projects radially through a slot in the main shaft 15. The pin 102 has secured on it a cam piece 104 outside the main shaft. 5

The disc-like member 72 is formed with a coned recess 106 to be engaged by a leather covered part 108 on a clutch member 110 keyed to and slidingly mounted on the main shaft 15. The right face of part 108 is arranged to be moved 16 towards the right, when the machine is to be stopped, into engagement with a leather braking ring 112 secured on the left face of a clutch supporting bracket 114. The clutch member 110 has a hub member on its right surrounding the 15 main shaft and having an inclined groove 114 around its periphery. Freely mounted in groove 114 is a swash ring 116 having extending from it a little below the axis thereof pins 118 which are rotatably mounted in a swinging lever 120 20 surrounding the hub of clutch member 110. The lever 120 has formed on it a ball 122 confined in spherical recesses in the ends of two axially aligned screws 124 adjustably mounted in clutch supporting bracket 114 parallel to the main 25 shaft. The lower side of lever 120 has pivoted on a pin 126 fixed in it a block 128 arranged to be engaged by a block 130 forming a hook on a clutch-controlling lever 132. When the hooked end of lever 132 engages the block 128 on lever 30 120 the part 108 of the clutch member 110 is held out of engagement with the recess 106 in member 110 against the action of springs 134 mounted in recesses formed in the hub of the clutch member 110 and engaging a collar 135 on the main shaft 35 15, which springs tend to thrust the coned part of the clutch member into engagement with the recess 106. Also when the hooked end of the clutch lever is in engagement with the block on the swinging lever, the right face of the coned 40 part of the clutch member 110 is brought into engagement with the leather braking ring 112 on the left end of bracket 114 to stop the machine. The clutch member 110 rides into engagement with the driving member 72 when the clutch lever 132 is out of engagement with the block 128 and because the pins 118 are below the axis 45 of the main shaft 15 the swinging lever is caused to swing idly about the ball 122. When, however, the clutch lever 132 is allowed to engage the 50 block 128 the swinging lever is prevented from swinging towards the left and is held stationary so that the clutch member 110 is moved to the right, withdrawing it from engagement with the disc-like member 72 and moving the clutch 55 member into engagement with the clutch supporting bracket to stop the machine. As will be clear from what has already been said, when the clutch lever 132 is moved downwardly away from the block 128, the springs 134 in the clutch member move the clutch member towards the left so as to disengage it from the bracket 114 and move it into engagement with the disc-like member 72 to drive the machine.

The clutch lever 132 is secured mid-way of its 65 length on a horizontal shaft 136 rotatably mounted in the bracket 114 and the right arm of the lever 132 has a horizontal pivot 138 carrying a spring latch 140. The rear end of shaft 136 to which the clutch lever 132 is secured has 70 fixed on it an arm 141 and has threaded through it a vertical adjustable screw 142 arranged to be engaged by the upper end of a cam member 144 secured on a shaft 146 rotatably mounted in a bearing on the bracket 114. The shaft 146 has 75

fixed to it an arm 148 which is connected by a rod 150 to the treadle 54. This arrangement is such that during depression of the treadle 54 the upper end of the cam member 144 engages the lower end of the screw 142 in the arm 140 and thereby rocks shaft 136 in a direction to disengage the hooked end of the clutch lever 132 from the block 128 to allow the clutch to be closed. Pivotaly mounted on a stud 152 fixed in the bracket 114 is a cam lever 154. The lower end of the cam lever has on it a roll 156 (Fig. 6) actuated by a cam face 158 on cam 144. The lower end of cam lever 154 also has fixed on it a plate 160 over which latch 140 snaps when the treadle is pressed fully down. The upper arm of cam lever 154 has formed on it a ball 162 which enters a recess in a lever 164 (Figs. 5 and 7) forming part of the mechanism for providing certain auxiliary movements to the stitching devices. The forward end of lever 164 is arranged at different times to be engaged by the cam piece 104 and also by a cam 166 on the main shaft. The rear end of lever 164 is secured to a substantially vertical pin 168 rotatably mounted in a block 170 secured to a rocking shaft 172 rotatably mounted in bearings at the rear of the machine so that lever 164 can swing to rotate the rocking shaft 172 and can swing laterally so that its forward end moves along the main shaft. The pin 168 to which lever 164 is secured has fixed on its upper end a finger piece 174 the end of which enters a recess in a spring pressed horizontal plunger 176 (Fig. 5) mounted in block 170. The plunger 176 is arranged to engage a pin 178 fixed on the machine frame when lever 164 is raised to hold the lever in this position.

When the machine is to be stopped, the small pulley 28 on the countershaft 18 is coupled to the driving member 40, the relatively large pulley 32 on the main shaft 15 being thereby driven. The small pulley 38 on the main shaft 15 will rotate idly the relatively large pulley 24 on the countershaft 18, which pulley at this time is freely rotatable on the countershaft. The lever 164 will in previous stopping of the machine have been raised by its cam 166 on the main shaft and will be held in raised position by the spring plunger 176 and will, through the rocking shaft 172, be holding certain of the stitching devices in proper positions to facilitate starting the machine. When the treadle 54 is first depressed the cam member 144 is swung upwardly and through the vertical lever 154 which it actuates, swinging lever 164 away from its cam 166 and releasing the spring plunger 176 so that lever 164 can swing downwardly towards the main shaft and shaft 172 can rotate to allow the stitching devices to return to their operating positions. Upon further depression of the treadle, the upper end of cam member 144 engages the lower end of screw 142 on the clutch lever and rocks shaft 136 in a direction to disengage the hooked end of the clutch lever from block 128 and allows the clutch to close, the machine being driven at the slow speed. When the treadle is still further depressed the right arm of lever 132 is raised still further by the cam 144 until latch 140 engages plate 160 on the lower end of cam lever 154 and during this further downward movement of the treadle the driving member 40 on the countershaft 18 is moved along the shaft out of engagement with small pulley 28 on the countershaft and into engagement with large pulley 34, the machine being then driven at the high speed. When the machine is being driven at high speed large pulley 32 on the main

shaft is being driven by the engagement of the recess 84 in the periphery of the disc-like member 72 with the block 82 on the inner face of large pulley 32 and small pulley 28 on the countershaft then disengaged from the driving member 40 on the countershaft, is driven idly. Owing to the fact that recess 84 in the disc-like member 72 is wider than the block 82 relative movement about the axis of the main shaft between member 72 and large pulley 32 takes place when the speed of the main shaft is changed from the low speed to the high speed and vice versa. This relative movement causes lever 88 to swing about its pivot 92 and through its wedge-shaped inner end 89 to move stem 90 and rod 96. The springs 98 urge the rod towards the right and hold one face of the recess in the stem 90 against the swinging lever 88. The arrangement is such that when the machine is being driven at the high speed the cam 104 secured to the rod 96 is at the right end of its movement along the main shaft and when the machine is being driven at the low speed the cam 104 is at the left end of its movement. When the cam is at the right end of its movement, it is removed from beneath lever 164 and when it is at the left end of its movement it is beneath said lever and raises the forward end of this lever.

If, when the machine is being driven at the high speed, it is desired that it shall be driven at the slow speed, the treadle 54 may be allowed to rise so far only that the driving member 40 on countershaft 18 moves out of engagement with large pulley 34 and into engagement with small pulley 28. When the change of speed takes place, the relative movement between member 72 and large pulley 32 on the main shaft takes place due to the application of driving force through the large pulley and cam 104 is moved to the left along the main shaft and comes beneath the end of lever 164. As the main shaft rotates, the lever 164 is raised somewhat by the cam 104 but the lever is prevented from swinging laterally by reason of its being held in its left-hand position by cam 144 and lever 154 which the cam operates. While the main shaft 15 is being driven at the slow speed, the clutch lever 132 is held in its inoperative position by the engagement of latch 140 on the right arm of lever 132 with plate 160 on lever 154. The lever 154 is held in place at this time by the cam 144 so that when the treadle 54 is allowed to rise, the cam being lowered, the clutch lever 132 is rendered operative without further delay.

When the treadle is allowed to rise fully, cam 144 which it operates releases the lever 154 and, when cam 104 raises the lever 164, this lever can swing to the right over cam 166 on the main shaft, when a low part of the latter cam comes into a position to allow it to do so. When a high part of cam 166 engages lever 164 as the cam rotates, this lever is rocked upwardly, thereby rotating shaft 172 in a direction to move certain of the stitching devices to predetermined positions. Lever 164 is held in its raised position by plunger 176 during any further rotation of the main shaft. When lever 164 swings to the right after being raised by cam 104 it swings the lower end of lever 154 to the left and releases latch 140 on the right arm of lever 132 from plate 160 on the lower end of lever 154, so that the left end of the clutch lever 132 can be raised, by a spring, not shown, to position the hooked end of the lever in the path of the block 128 on lever 120. Thereafter the lower end of lever 120 moves to the left and its swinging movement is stopped. As the

main shaft continues to rotate, the clutch member 110 is moved out of engagement with the disc-like member 72 and into engagement with the braking ring 112 on the clutch bracket 114 to stop the main shaft.

It will be seen that this stopping arrangement is such as to bring the machine to rest always at the same point in the machine cycle without undue shock, even though the machine be running at high speed and the treadle be completely released suddenly. The definiteness of the stopping position is assured by the fact that the application of the brake is directly controlled by the swash ring 116 on the main shaft 15 while the absence of shock is due to the impossibility of the swash ring becoming operative until the speed of the main shaft has fallen to the low driving speed, for it is only when the low speed driving pulley on the main shaft 15 catches up the high speed pulley that the lost motion device consisting of the block 82 on the low speed pulley 32 and the recess 84 in the disc-like member 72 becomes active to stop the machine.

25 The nature and scope of the invention having been indicated, and a construction embodying the several features of the invention having been specifically described, what is claimed is:—

1. A driving and stopping mechanism having, 30 in combination, a driven shaft, a main driving clutch, high and low speed driving mechanism for driving the main clutch comprising high and low speed friction clutches, a treadle, treadle controlled connections acting to close the high speed clutch as the low speed clutch is opened and to close the low speed clutch as the high speed clutch is opened, and means controlled both by said treadle and by the application of a driving force through the low speed driving mechanism for opening the main clutch.

40 2. A driving and stopping mechanism having, in combination, a driven shaft, a main driving clutch, high and low speed driving mechanism for driving the main clutch, means for shifting from the high to the low speed driving mechanism, and means actuated by a change in speed of said shaft while the low speed driving mechanism is operative for opening the main driving clutch.

50 3. A driving and stopping mechanism having, in combination, a driven shaft, a main driving clutch, high and low speed driving mechanism for driving the main clutch comprising high and low speed friction clutches, a treadle and suitable connections for controlling the friction clutches to shift from high to low speed, normally inoperative means actuated by said shaft for opening the main clutch, and an element controlled by a change in speed of the driven shaft for rendering the main clutch opening means operative.

65 4. A driving and stopping mechanism having, in combination, a driven shaft, a main driving clutch, a vibrating member actuated by the shaft and cooperating therewith when held from vibration to open the clutch, a latch to hold the member from vibration, high and low speed driving mechanisms for driving the clutch, and means controlled by the low speed driving mechanism and actuated by the shaft for causing the latch to engage the vibrating member.

70 5. A driving and stopping mechanism having, in combination, a driven shaft, a main driving clutch comprising driving and driven members, a high speed pulley directly connected to the

driving clutch member, a low speed pulley concentric with the high speed pulley and having a limited angular movement with relation thereto, and means actuated by the shaft and controlled by said angular movement of the slow speed pulley for opening the clutch while the shaft is being driven by the slow speed pulley.

6. A driving and stopping mechanism having, in combination, a driven shaft, a main driving clutch, high and low speed driving mechanisms 10 for driving the clutch comprising high and low speed friction clutches, a treadle and suitable connections for controlling the friction clutches to drive the main clutch at either a high or a low speed, means actuated by the shaft to open 15 the main clutch, said means comprising a trip member arranged to be actuated by the treadle, an element for preventing actuation of said trip member, and means controlled by the application of a driving force through the low speed 20 clutch for rendering the trip member operative to open the main clutch.

7. A driving and stopping mechanism having, in combination, a main shaft, a main clutch therefor, high speed and low speed clutches for 25 driving said main clutch at high or low speed at the will of the operator, and means rendered operative by a change in speed of rotation of the main shaft for opening the main driving clutch.

30 8. A driving and stopping mechanism having, in combination, a main shaft, a main clutch on said shaft comprising a driving and a driven member, a high speed pulley directly connected to the driving member, a low speed pulley having a 35 limited angular movement relatively to the high speed pulley and controlled by the said angular movement of the low speed pulley for opening the clutch while the shaft is being driven by the low speed pulley.

40 9. A driving and stopping mechanism having, in combination, a main shaft, high and low speed clutches for driving said shaft at high speed or low speed at will, means for ensuring that, on the starting of the machine into operation, the 45 low speed clutch will come into driving operation before the high speed clutch and will remain in driving operation after the high speed clutch has been disengaged, and means controlled by the application of a driving force through the low 50 speed clutch for stopping the machine.

10. A driving and stopping mechanism having, in combination, a main shaft, a main clutch on said shaft comprising a driving and a driven member, a high speed pulley directly connected 55 to the driving member, a low speed pulley having a limited angular movement relatively to the high speed pulley, a cam on the shaft, means actuated by the main clutch shaft comprising a trip lever arranged to be actuated by the cam when 60 it is being driven at low speed, and a controlling device for said trip lever arranged to prevent actuation of it by said cam when the shaft is rotating at high speed, but to release it for actuation by the cam when the machine has fallen to 65 low speed.

11. A driving and stopping mechanism having, in combination, a main driven shaft, a main driving clutch comprising driving and driven members, high and low speed driving mechanisms 70 for rotating the driving clutch member, a treadle for closing the main clutch and for rendering either of said mechanisms effective at will, and means actuated by the treadle when the main shaft is rotated at low speed and by the low speed 75

driving mechanism when the shaft is driven at high speed for opening the main clutch.

12. A driving and stopping mechanism having, in combination, a main driven shaft, a main driving clutch comprising driving and driven members, high and low speed driving mechanisms for rotating the driving clutch member, a treadle for closing the main clutch and for rendering either of said mechanisms effective at will, and means actuated by the driving force of said driving mechanisms when the speed of the shaft is above the speed of the low speed driving mechanism for preventing the main clutch from being opened.

13. A driving and stopping mechanism having, in combination, a main driven shaft, a main driving clutch comprising driving and driven members, high and low speed driving mechanisms for rotating the driving clutch member, a treadle for closing the main clutch and for rendering either of said mechanisms effective at will, a trip member arranged to hold the main clutch closed after the high speed driving mechanism is rendered effective by the treadle, and connections actuated by the application of a driving force through the low speed driving mechanism to release the trip member and cause the main clutch to be opened.

14. A driving and stopping mechanism having, in combination, a main driven shaft, a main driving clutch comprising driving and driven members, a counter-shaft, high and low speed clutches on the counter-shaft, driving connections for rotating the main driving clutch member from said high and low speed clutches, a treadle for causing the low speed clutch to be closed when the high speed clutch is opened, the low speed clutch to be opened when high speed clutch is closed, and the main clutch to be opened only when the low speed clutch is closed, and an element shiftable by a change in speed of the main shaft to prevent opening of the main clutch while the main shaft is rotated at high speed.

15. A driving and stopping mechanism having, in combination, a main driven shaft, a main driving clutch comprising driving and driven members, a counter-shaft, high and low speed clutches on the counter-shaft, driving connections for rotating the main driving clutch member from said high and low speed clutches, a treadle for causing the low speed clutch to be closed when the high speed clutch is opened, the low speed clutch to be opened when the high speed clutch is closed, and the main clutch to be opened only when the low speed clutch is closed, and means actuated by a change in speed of the main shaft for delaying the opening of the main clutch after the high speed clutch is opened.

16. A driving and stopping mechanism having, in combination, a main driven shaft, a main driving clutch comprising driving and driven members, high and low speed driving mechanisms for rotating the driving clutch member, a treadle for closing the main clutch and for rendering either of said mechanisms effective at will, a trip member arranged to hold the main clutch closed after the high speed driving mechanism is rendered

effective by the treadle, a cam on the main shaft for releasing the trip member, and connections controlled by the low speed driving mechanism when the speed of the shaft is above the speed of the low speed driving mechanism for preventing the cam from releasing the trip member.

17. A driving and stopping mechanism having, in combination, a main driven shaft, a main driving clutch comprising driving and driven members, high and low speed driving mechanisms for rotating the driving clutch member, a treadle for closing the main clutch and for rendering either of said mechanisms effective at will, a trip member arranged to hold the main clutch closed after the high speed driving mechanism is rendered effective by the treadle, a cam on the main shaft, a follower normally out of the range of the cam for releasing the trip member when actuated by the cam, and connections controlled by the low speed driving mechanism when the speed of the shaft is the same as the speed of the low speed driving mechanism to bring the follower into the range of the cam.

18. A driving and stopping mechanism having, in combination, a main driven shaft, a main driving clutch comprising driving and driven members, high and low speed driving mechanisms for rotating the driving clutch member, a treadle for closing the main clutch and for rendering either of said mechanisms effective at will, a trip member arranged to hold the main clutch closed after the high speed driving mechanism is rendered effective by the treadle, a lever for releasing the trip member, a cam on the main shaft normally out of position to engage the lever, and connections controlled by the low speed driving mechanism when the speed of the shaft is the same as the speed of the low speed driving mechanism to bring the cam into a position where it will engage the lever.

19. A driving and stopping mechanism having, in combination, a main shaft, a main clutch on the shaft, a brake for bringing the shaft to rest, means including a cam on the shaft for causing the clutch to be opened and the brake to be applied at predetermined angular positions of the shaft, a rod arranged in parallel relation to and rotating with the shaft for changing the position of the cam to render it effective or ineffective in stopping the shaft, and means for actuating the rod.

20. A driving and stopping mechanism having, in combination, a main shaft, a main clutch on the shaft, a brake for bringing the shaft to rest, means including a cam on the shaft for causing the clutch to be opened and the brake to be applied at predetermined angular positions of the shaft, a rod arranged in parallel relation to and rotating with the shaft for changing the position of the cam to render it effective or ineffective in stopping the shaft, and means for shifting the rod to cause the cam to be ineffective when the shaft is rotating above a predetermined speed.
